UNITED STATES PATENT OFFICE.

ALBERT J. ROWAN, OF PROVIDENCE, RHODE ISLAND, ASSIGNOR TO PAYTON & KELLY CO., OF PROVIDENCE, RHODE ISLAND, A CORPORATION OF RHODE ISLAND.

DESIGN FOR A DECORATED TUBE.

Application filed July 6, 1926. Serial No. 18,258. Term of patent 3½ years.

To all whom it may concern:

Be it known that I, ALBERT J. ROWAN, a citizen of the United States, residing in Providence, county of Providence, and State of Rhode Island, have invented a new, original, and ornamental Design for a Decorated Tube, of which the following is a specification, reference being had to the accompanying drawing, forming a part thereof.

The dominant feature of this design consists of a helically disposed relatively narrow band encircling a length of tubing.

The figure is a side elevation of a decorated tube, showing my new design.

I claim:

The ornamental design for a decorated tube, substantially as shown and described.

ALBERT J. ROWAN.
